(57) **CLAIM**

The ornamental design for an inflatable monotub, as shown and described.

DESCRIPTION

FIG. 1 is a perspective view of a first side of a first embodiment of the inflatable monotub;

FIG. 2 is a perspective view of the first side of the inflatable monotub shown in FIG. 1;

FIG. 3 is a perspective view of a second side of the inflatable monotub shown in FIG. 1;

FIG. 4 is a perspective view of a third side of the inflatable monotub shown in FIG. 1;

FIG. 5 is a perspective view of a fourth side of the inflatable monotub shown in FIG. 1;

FIG. 6 is a view of a top of the inflatable monotub shown in FIG. 1;

FIG. 7 is a view of a bottom of the inflatable monotub shown in FIG. 1;

FIG. 8 is a cross-sectional perspective view of the third side of the inflatable monotub shown in FIG. 4;

FIG. 9 is a perspective view of a first side of a second embodiment of an inflatable monotube;

FIG. 10 is a perspective view of the first side of the inflatable monotub shown in FIG. 9;

FIG. 11 is a perspective view of a second side of the inflatable monotub shown in FIG. 9;

FIG. 12 is a perspective view of a third side of the inflatable monotub shown in FIG. 9;

FIG. 13 is a perspective view of a fourth side of the inflatable monotub shown in FIG. 9;

FIG. 14 is a view of a top of the inflatable monotub shown in FIG. 9;

FIG. 15 is a view of a bottom of the inflatable monotub shown in FIG. 9; and,

FIG. 16 is a cross-sectional perspective view of the third side of the inflatable monotub shown in FIG. 12.

The broken lines shown are for the purpose of illustrating portions of the inflatable monotub that forms no part of the claimed design.
